INVENTOR

Carl R. Houghton,
BY
Arthur M. Hood.
ATTORNEY

UNITED STATES PATENT OFFICE.

CARL R. HOUGHTON, OF CONNERSVILLE, INDIANA, ASSIGNOR TO CONNERSVILLE BLOWER COMPANY, OF CONNERSVILLE, INDIANA, A CORPORATION OF INDIANA.

GOVERNOR.

Application filed May 5, 1923. Serial No. 636,920.

To all whom it may concern:

Be it known that I, CARL R. HOUGHTON, a citizen of the United States, residing at Connersville, in the county of Fayette and 5 State of Indiana, have invented a new and useful Governor, of which the following is a specification.

My invention relates to improvements in governors for prime movers and particularly to pressure responsive governors 10 therefor.

It is one of the objects of my invention to provide means for stabilizing the action of governors of the above type to prevent 15 hunting. Another object of my invention is to provide means for controlling the prime mover of gas exhausters and the like, which means may be readily and easily adjustable to obtain the most desirable 20 results.

For the purpose of disclosing my invention I have illustrated one embodiment thereof in the accompanying drawings in which—

25 Fig. 1 is a side elevation of an exhauster and governor embodying my invention, some of the parts thereof being shown in section, and

30 Fig. 2 is a central vertical section through the pilot valve which is operated by the pressure governor.

In the embodiment of the invention illustrated the exhauster 10 is driven by the usual engine 11 or other prime mover and 35 draws gas from the gas suction main 12 and discharges it into the main 13, which two mains are connected to the collecting mains of the oven batteries and to the mains of a gas handling plant.

40 The steam for the engine is supplied through a pipe 14 and the supply of steam is controlled by a lever 15 which may be any control lever for any desired kind of engine control. The lever 15 is operable by an arm 16 provided with a counterweight 17 and the arm 16 is connected to the piston rod 18 of a piston 19 movable vertically in the cylinder 20 so that when the piston 19 rises the arm 16 works the lever 15 to reduce the engine's speed and vice versa. The cylinder 20, together with its piston 19 and the connection rod 18 and lever 16 constitute a pressure responsive device connected to the control member of the engine 50 for controlling the steam supply thereto.

For safety I also provide a ball governor 21 responsive to the engine's speed but the ball governor is arranged to come into play only when the speed of the exhauster rises unduly high so that it plays no part in the 60 regular controlling action and is merely a safety device.

The lower part of the cylinder 20 is connected to an air supply pipe 22 and to an air outlet pipe 23, both of which communicate with the cylinder 20 below the lowest point to which the piston 19 can move. The air supply pipe 22 is connected to the outlet of a small blower 24 preferably a 70 rotary positive pressure blower, which is driven in any suitable manner from the exhauster 10 so that the speed of the blower and of the exhauster vary in proportion. As shown, the driving of the blower 24 is by an ordinary belt 25 but this is merely 75 one illustration.

Connected to the air supply pipe 22 is a bleeder valve 26 which is operable by an arm 27 connected by a link 28 with the lever 16. The link 28 is connected to the 80 lever 16 by a suitable bolt or pin adapted to pass through one of a series of openings 29 in the lever so that the link may be connected at one of a number of points along the length of the lever and the lower 85 end of the link is likewise connected to the arm 27, this arm being provided with a series of holes 30. As the speed of the exhauster 10 increases, the speed of, and consequently the quantity of air discharged 90 by, the blower is proportionately increased.

The air outlet pipe 23 leads from the cylinder 20 to a pilot valve 31 which is shown in detail in Fig. 2. This pilot valve is a continuous leakage valve, the amount 95 of leakage depending upon the position of the valve stem 32. The valve stem 32 projects through the end walls of a chamber 33 into which the pipe 23 leads and the stem is provided at such end walls with 100 cut away portions 34 which allow the escape of air from the chamber 33 at a rate depending upon the position of the stem 32. The cut away portions 34 are so arranged that a balance of the leakage air 105 through the two end walls is obtained and the stem thereby maintained in a balanced condition. In addition to the pilot valve 31 I provide in the pipe 23, a hand controlled leakage valve 35 which may be ma- 110

nipulated to provide for a constant leakage from the pipe 23 independent of the valve 31.

The stem 32 of the pilot valve is connected by a link 36 to a lever 37 provided with arc shaped ends to get constant lengths of effective lever arms. The float 38 of the gasometer hangs from one end of the lever 37 and a counterweight from the other. The float 38 is vertically movable as a gasometer float in an open topped water container 39 of the gasometer and the pipe 40 which communicates with the gas suction main 12 opens beneath the float 38 so that the pressure beneath such float is that existing within the gas suction main. It is thus seen that the container 39, together with the float 38, constitute a pressure responsive device responsive to pressure in the gas main for controlling the leakage of pilot valve 30.

In operation, the exhauster 10 draws gas from the gas suction main 12 and discharges it into the discharge main 13. The blower supplies air through the pipe 22 into the cylinder 20 beneath the piston 19 and more or less of the air thus supplied to the cylinder escapes therefrom through the pipe 23 and pilot valve 31, the amount escaping depending upon the position of the stem 32 of the pilot valve. The air pressure beneath the piston 19 raises such piston to a greater or less height and thus moves the control lever 15 more or less. The movement of the control lever affects the valve 26 and as the piston moves upward the bleed valve gradually opens to permit a greater quantity of the air to escape and thereby stabilize the action of the governor. If for any reason the speed of the exhauster increases as, because of, a change in steam pressure or of a change due to the movement of the float 38 as hereinafter described, the speed of the blower changes correspondingly and the pressure beneath the piston 19 is correspondingly increased. This increased pressure raises the piston 19 and moves the control lever 15 in the proper direction to produce slowing down of the engine until the pressure beneath the piston is the same as it was before (though the piston may be in a different position than at first,) which return of the pressure beneath the piston to its original value does not occur until the speed of the blower 24, and therefore the exhauster, is the same as it was before. This results in constant speed control of the engine and prevents objectionable surging and hunting. If the quantity of gas supplied through the gas suction main 12 changes, the pressure in said main changes correspondingly and the gasometer float 38 rises or falls. This movement of the float 38 moves the stem 32 of the valve 31 to allow more or less air to escape at

the pilot valve and such change in the air leakage produces a downward or upward movement of the piston 19 to operate the control lever 15 to increase or decrease the steam supply and thus make the exhauster 10 and blower 24 run at a greater or less speed to correct for this difference in air leakage and thus to take care of the change in quantity of gas supplied through the gas suction main 12.

The float 38 is preferably provided with a nearly closed bottom 41 so that the water may pass into, or out of, the float only at a slow rate. This makes the movement of the float relatively sluggish and dead beat and assists in preventing any hunting or surging action. By providing the valve 35 I am enabled to supplement the air leakage through the pilot valve 31. In case the governing action, above described, fails for any reason and the speed of the engine and exhauster rises unduly, the ball governor comes into play and prevents the engine from running away.

I claim as my invention:

1. In combination, a prime mover, an apparatus driven thereby, a control member for controlling the supply of energy to said prime mover, a pressure responsive device connected to said control member to operate it, a pump the speed of which is varied by the variation in the speed of the driven apparatus and supplying fluid to the pressure responsive device and means caused to operate by the operation of said pressure device for bleeding the fluid supplied to said pressure responsive device in proportion to the movement thereof. 90
2. In combination, a prime mover, an apparatus driven thereby, a control member for controlling the supply of energy to said prime mover, a pressure responsive device connected to said control member to operate it, a pump arranged to operate at a speed proportional to that of the driven apparatus and supplying fluid to said pressure responsive device, a bleed valve for said fluid and means for increasingly opening said valve as said pressure responsive device moves to decrease the supply of energy to the prime mover. 95
3. In combination, a prime mover, an apparatus driven thereby, a control member controlling the supply of energy to said prime mover, a cylinder, a piston operating therein and connected to the control member to operate it, a pump the speed of which is varied by the variation in the speed of the driven apparatus and supplying fluid to said cylinder, a bleeder valve for said cylinder, and a connection between said valve and piston to operate the valve proportionately to the movement of said piston. 100
4. In combination, a prime mover, an apparatus driven thereby, a control member 110

for controlling the energy supplied to said prime mover, a pressure responsive device connected to said control member to operate it, a pump arranged to operate at a speed proportional to that of the driven apparatus and supplying fluid to said pressure responsive device, means for bleeding the fluid supplied to said pressure responsive device in proportion to the movement thereof and a governor operated leakage valve connected to said pressure responsive device.

5. In combination, a prime mover, an apparatus driven thereby, a control member for controlling the energy supplied to said prime mover, a pressure responsive device connected to said control member to operate it, a pump arranged to be driven at a speed proportional to the speed of the driven apparatus and supplying fluid to said pressure responsive device, means for bleeding the fluid supplied to said pressure responsive device in proportion to the movement thereof, a leakage valve connected to said pressure responsive device and a second pressure responsive device for controlling said leakage valve.

6. In combination, a prime mover, an apparatus driven thereby, a control member for controlling the supply of energy to said prime mover, a pressure responsive device connected to said control member to operate it, a pump arranged to operate at a speed proportional to that of the driven apparatus and supplying fluid to the pressure responsive device, means for bleeding the fluid supply to said pressure responsive device in proportion to the movement thereof, a leakage valve connected to said pressure responsive device, a second pressure responsive device controlling said leakage valve and a manually controlled leakage valve connected

to said first mentioned pressure responsive device.

7. In combination, an exhauster drawing gas from the gas suction main and discharging it into the discharge main of a gas plant, an engine for operating said exhauster, a control member for controlling the supply of energy to said engine, a pressure responsive device connected to said control member to operate it, a pump arranged to operate at a speed proportional to that of the exhauster and supplying fluid to said pressure responsive device, a bleeder valve for said pressure responsive device and means for increasingly opening said bleeder valve in proportion to the movement of said pressure responsive device to decrease the energy supplied to the engine, a leakage valve connected to said pressure responsive device and a second pressure responsive device responsive to the pressure in said gas suction main and controlling said leakage valve.

8. In combination, a prime mover, an apparatus driven thereby, a control member for controlling the supply of energy to said prime mover, a pressure responsive device connected to said control member to operate it, a pump driven at a speed proportional to the speed of the driven apparatus and supplying fluid to said pressure responsive device, means for bleeding the fluid supplied to said pressure responsive device in proportion to the movement thereof, and a manually operated leakage valve connected to said pressure responsive device for adjusting the speed of the prime mover.

In witness whereof I, CARL R. HOUGHTON, have hereunto set my hand at Connersville, Indiana, this 30th day of April, A. D., one thousand nine hundred and twenty three.

CARL R. HOUGHTON.
